LOCOMOTIVE COMBUSTION CONTROL

Fred D. Mosher, Erie, Pa., assignor to The Standard Stoker Company, Incorporated, a corporation of Delaware

Application November 6, 1947, Serial No. 784,365

6 Claims. (Cl. 236—26)

1

This invention relates to coal fired steam locomotives and more particularly to an improved combustion control system for regulating the fuel and air supply to the locomotive firebox.

Among the broader objects of my invention are the provision of an improved coal fired locomotive having greater availability, reliability and lower overall operating costs than prior coal fired steam locomotives; and in which firing and care of the fire requires a minimum of attention by the engine crew, thereby permitting the crew more time for other duties; and in which greater combustion efficiency is realized, thereby contributing to reduction in smoke and decreased fuel costs; and in which longer stand-by time is permitted without manual attention to the fire.

In attaining these objects it is important that the coal and the air for combustion be supplied in the proper ratio and in amounts proportional to the demand being made upon the boiler for steam. At the present time the amount of coal supplied to the firebox, either manually or by a mechanical stoker, is controlled by the fireman, and whether through the fireman's neglect or due to the fact that he is attending to other duties, coal is not consistently supplied to the firebox in amounts proportional to the demand upon the boiler for steam.

Means of controlling draft with a conventional locomotive nozzle or by mechanical drafting, to supply air consistently in amounts proportional to the demand being made upon the boiler for steam have heretofore not been successful.

It is, therefore, a further object of my invention to provide a combustion control system whereby coal from a mechanical stoker and air from a turbine driven induced draft fan, are supplied to the firebox in a substantially constant pre-selected ratio and whereby the coal and air, in such pre-selected ratio, is supplied to the firebox in an amount proportional to the demand upon the boiler for steam, and is automatically varied in accordance with such demand.

Another object of the invention is to provide an automatic combustion control system for a mechanically drafted and mechanically fired boiler of the foregoing type, for sequential operation of the draft inducing fan and the stoker, whereby the draft inducing fan will start first, followed by the steam jets that project the coal over the firebed, and finally followed by operation of the coal conveying mechanism of the stoker.

Another object of the invention is to provide a combustion control system of the type described for application to a locomotive, wherein the ash

2

pan dampers of the locomotive firebox are automatically closed upon cessation of operation of the draft inducing fan and automatically opened on operation of the draft inducing fan.

Additional objects, advantages and features of invention reside in the construction, arrangement and combination of parts, as will be understood from the preferred and practical embodiment of the invention hereinafter described and illustrated in the accompanying drawings, in which:

Fig. 1 is a side elevation of the rearward portion of a locomotive with portions of the cab removed, showing the invention applied thereto;

Fig. 2 is a rear end elevation of the locomotive with portions of the cab broken away, showing the invention applied thereto;

Fig. 3 is a central vertical longitudinal section through the forward end of the locomotive, equipped in accordance with the present invention, some parts being shown in elevation;

Fig. 4 is a fragmentary front elevation of the locomotive firebox and ash pan, with the ash pan dampers and operating mechanism therefor, shown applied thereto;

Fig. 5 is a fragmentary side elevation of the locomotive firebox and ash pan, viewing it from the left side of Fig. 4, with the ash pan damper and operating mechanism therefor, shown applied thereto;

Fig. 6 is a sectional view taken on the line 6—6 of Fig. 5;

Fig. 7 is a sectional view taken on the line 7—7 of Fig. 5; and

Fig. 8 is a schematic or diagrammatic representation of the control system for the stoker engine, stoker distributor jets, the induced draft fan turbine and the dampers.

With particular reference to Figs. 1 and 2 of the drawings, the locomotive is indicated generally by the letter L and includes the main frame 10, the cab 11 and cab deck 12. At 13 there is shown the backhead of the firebox 14. The backhead 13 has an opening (not shown) therethrough arranged to form both a hand firing opening and a stoker firing opening, a power operated fire-door 15 being arranged to form a closure for the upper portion of the firing opening, and a discharge conduit 16 of a stoker 9 communicating with the lower portion of the firing opening.

The boiler barrel 17 extends forwardly from the firebox 14 and is traversed by a plurality of firetubes 18 through which the combustion gases pass from the firebox 14 to the smoke box 19, as

shown in Fig. 3. Steam delivered from the boiler to the dry pipe 20 flows through the header 21 and is then delivered to a pair of steam pipes, one of which is shown at 22 in Fig. 3, which, as usual, lead to the inlet steam ports in the cylinder castings (not shown). Exhaust steam from the cylinders passes to atmosphere through the exhaust pipe 23 and exhaust stack 24 which projects through the compartment 25 of the smoke box 19.

Banks of inverted V-shaped angle irons forming a screen 26 separate the compartment 25 of the smoke box 19 from the compartment 21 thereof. The screen 26 serves to separate cinders entrained in the combustion gases, and the cinders collecting at the bottom of the compartment 25 may be withdrawn and disposed of in any manner desired.

In a compartment 28 forward of the compartment 21, there is mounted a steam turbine 29 provided with a shaft 30 carrying a blower fan 31. The blower fan operates in the usual manner and sets up a draft which draws the products of combustion from the firebox 14 through the flues 18 into the smoke box 19 and then into the circumferentially arranged flared tubular member 32 mounted on a wall 33 separating compartments 21 and 28, and registering with an opening 34 in the wall 33. All of the gases and products of combustion must therefore pass through the fan 31 and will be discharged therefrom into the compartment 28 from whence they escape through the stack 35.

Live steam is admitted to the turbine 29 at 36 in the manner hereinafter described, and the steam, after passing through the turbine, is discharged through the outlet 37 into the compartment 28 and thence out through the stack 35.

Referring now to Figs. 1, 4 and 5, the numeral 38 designates the locomotive ash pan disposed beneath the firebox 14. The ash pan 38 is provided along its opposite sides with the dampers 39 and 40 which control the air admission openings between the mud ring (not shown) of the firebox 14 and the ash pan 38.

The dampers 39 and 40 are L-shaped in cross section and are mounted to swing as the longitudinally extending rods 41 and 42, respectively, are rotated. Referring specifically to Fig. 4, the dampers 39 and 40 are shown in their open position, as indicated in full lines, while the dot and dash lines indicate the position of the dampers 39 and 40 when they assume their closed position.

The rod 42 is rotatably mounted subjacent the outer side edge of the ash pan 38 in the looped end 43 of the bracket 44 as best seen in Fig. 6. A plurality of such brackets is provided at spaced intervals, as shown in Fig. 1 and a similar mounting arrangement is provided for the rod 41 which extends longitudinally along the opposite side of the ash pan 38. Referring to Figs. 4 and 6, it will be seen that the brackets 44 are spaced from the under side of the ash pan 38 subjacent the outer side edges thereof by spacer members 45; and bolts 46 passing through the brackets 44, spacer members 45 and the ash pan 38, or other suitable means, may be employed to rigidly secure the brackets 44 to the ash pan 38.

The damper 40 is mounted to rotate with the rod 42 by means of a bracket 48 which is rigidly secured to the damper in any suitable manner, as by welding, and which is provided at one end with a looped portion 49, as best seen in Fig. 7, that fits about and is rigidly secured to the rod 42 in any suitable manner, as by welding. A plurality of such brackets is provided at spaced in-

tervals, as shown in Fig. 1 and a similar mounting arrangement is provided for the damper 39 which extends longitudinally along the opposite side of the ash pan 38.

The dampers 39 and 40 are operated by a steam motor cylinder 50 which is mounted on a bracket 51 rigidly secured to and depending from the mud ring (not shown) of the firebox. The cylinder piston 52 is connected by a link 53 with the lower end of a lever 54 which is secured intermediate its ends on the rod 42. Thus reciprocation of the piston (not shown) of the motor cylinder 50 will cause the rod 42 to alternately rotate first in one direction and then in the opposite direction, whereby the damper 40, which as previously explained is secured to the rod 42, is moved to its open or its closed position.

A rod 55 connects the upper end of the lever 54 with the lower end of the lever 56 which is rigidly secured intermediate its ends on the rod 41, and since the damper 39 is mounted to rotate with the rod 41, as previously explained, it will be seen that the dampers 39 and 40 act in unison. A tension spring 57 attached at one end to a rigid part of the locomotive and attached at its other end to the upper end of the lever 56, normally holds the dampers in closed position, as shown in dot and dash lines in Fig. 4. When steam is admitted to the motor cylinder 50, the dampers 39 and 40 are moved, through the operating connections above described, to their open position, as shown in full lines in Fig. 4.

Referring now to Fig. 8, which is a diagrammatic representation of the control system, steam for operating the stoker engine 58, the fan turbine 29, the damper motor cylinder 50, and the steam emitted from the stoker distributor jet head 59 for projecting the coal into the firebox, is supplied from the locomotive steam turret 60.

A steam line 61 leads from the steam turret 60 to the stoker engine 58, supplying steam for operating the latter which in turn operates the stoker screw conveyor for advancing coal from the coal bin of the tender to the stoker distributor jet head 59 adjacent the firing opening of the locomotive firebox 14.

Interposed in the steam line 61 is a diaphragm actuated valve 62 responsive to a control system hereinafter described, for operating the stoker engine and consequently the stoker screw conveyor to deliver coal to the firebox in an amount proportional to the demand being made upon the boiler for steam.

A valve controlled by-pass 63 is provided in the steam line 61 by-passing the diaphragm actuated valve 62 whereby the stoker engine 58, and consequently the stoker screw conveyor, may be operated independently of the control system.

A second steam line 64 leads from the steam turret 60 to the induced draft fan turbine 29, supplying steam to the turbine for operating the fan, which in turn effects an induced draft of air through the firebox to provide the necessary air to support combustion of the coal.

Interposed in the steam line 64 is a diaphragm actuated valve 65 responsive to the aforesaid control system, for operating the turbine 29 and consequently the fan 31, to provide an induced draft of air through the firebox in an amount proportional to the demand being made upon the boiler for steam.

A valve controlled by-pass 66 is provided in

the steam line 64 by-passing the diaphragm actuated valve 65 whereby the turbine 29, and consequently the induced draft fan 31, may be operated independently of the control system.

A steam line 67 branches off the steam line 64 at a point between the diaphragm valve 65 and the turbine 29 and communicates with the damper motor cylinder 50 for operating the dampers 39 and 40. Opening and closing of the dampers is thus also responsive to the control system and since the admission of steam to the damper cylinder 50 and cutting off of steam thereto is regulated by the same valve 65 that regulates admission of steam to the fan turbine 29 and cutting off of steam thereto, it will be seen that operation of the dampers is synchronized with operation of the induced draft fan.

A third steam line 68 leads from the steam turret 60 to the stoker distributor jet manifold 69. A plurality of steam supply pipes 70, preferably five as shown in Figure 8, lead from the manifold 69 to individual chambers (not shown) in the stoker distributor jet head 59. As well known in the art, and therefore not shown, the front face of the jet head 59 is provided with jet openings communicating with the chambers of the jet head 59, the jet openings being so directed that the pressure fluid jet streams emitted therefrom project the coal delivered by the stoker screw conveyor over all parts of the firebox. A regulating valve such as an ordinary globe or needle valve 71 is placed in each supply pipe 70 between the manifold 69 and the distributor jet head 59 to control the pressure of the coal projecting steam blasts.

Interposed in the steam line 68 is a diaphragm actuated valve 72 responsive to the aforesaid control system for permitting flow of steam to the manifold 69 and consequently the distributor jet head 59, and for interrupting the flow of steam thereto.

A valve controlled by-pass 73 is provided in the steam line 68 by-passing the diaphragm actuated valve 72 whereby steam may be supplied to the manifold 69, and consequently to the distributor jet head 59, independently of the control system.

The system for controlling the operation of the valves 62, 65 and 72 is operated by air supplied through the line 80 from the main reservoir (not shown) on the locomotive.

The controls consist primarily of three instruments mounted on a panel 81 in the left side of the backhead 13 of the firebox 14, as best shown in Fig. 2. These instruments are, namely, a steam-pressure controller 82 which actuates in the proper sequence other instruments, herein-after described, in the control system when the boiler pressure of the locomotive drops below the pressure for which the steam-pressure controller is set; a selector valve 83 permitting changing from automatic to hand control; and a ratio controller 84 whereby the desired ratio of air supplied to the coal fired may be controlled and varied as desired.

The instruments responsive to the steam-pressure controller are a relay valve 85 which controls the operation of the diaphragm valve 62 in the steam line 61 leading to the stoker engine 58; a relay valve 86 which controls the operation of the diaphragm valve 72 in the steam line 68 leading to the stoker distributor jet manifold 69; and a relay valve 87 which controls the operation of the diaphragm valve 65 in the steam

line 64 leading to the fan turbine 29 and the damper motor cylinder 50.

For purpose of illustration certain operating steam and air pressures will be assumed in the following description, it being understood, however, that these pressures may be altered depending on varying operating conditions.

Compressed air at 70-100 lb. per sq. in. is brought from the main reservoir (not shown) 10 of the locomotive through the air supply line 80. Interposed in the line 80 is a 28 lb. per sq. in reducing valve 88 and an air filter 89. The valve 90 in the by-pass line 91 which by-passes the reducing valve 88 and air filter 89 is normally closed, while valves 92 and 93, fore and aft of the reducing valve 88 and air filter 89, are normally open.

From the 28 lb. per sq. in. side of the air supply line 80, air is piped at that pressure to relay valves 95, 86 and 87 through the branch lines 94, 95 and 96, respectively; to the steam-pressure controller 82 through branch line 97; to the selector valve 83 through branch line 98; and to the ratio controller 84 through branch line 99.

The steam-pressure controller 82 is equipped with two hands, as shown in Fig. 2, a controlling hand 100 which can be set to maintain a desired pressure in the boiler, e. g. 200 lbs. per sq. in.; and an indicating hand 101, which shows the actual steam pressure in the boiler. Now, should the boiler pressure drop below 200 lbs. per sq. in., the indicator hand 101 will lag behind the controller hand 100, the steam-pressure controller 82 then permits an amount of the 28 lb. per sq. in. air supply, in proportion to the difference between the indicated and desired boiler pressure, to pass through the loading air line 102 and enter the selector valve 83 as a loading pressure.

The supply air entering the selector valve 83 through the branch supply line 98, thus leaves through the line 103 as a controlled air pressure. It is evident then, that as the indicated boiler pressure drops further and further below the boiler pressure for which the controlling hand 100 of the steam-pressure controller 82 is set, the amount of air passing through the line 102 increases, exerting a greater loading pressure on the selector valve 83, which in turn causes the selector valve 83 to open wider whereby a greater amount of air passes from the branch supply line 98 to the line 103. The air in the line 103 becomes controlled loading air, the pressure thereof fluctuating automatically as the demand for steam on the boiler increases or decreases.

The controlled loading pressure air line 103 is branched, with one branch line 104 leading to the ratio controller 84 and the other branch line 105 leading to the relay valve 85.

The controlled air loading pressure in the branch line 105 controls the operation of the relay valve 85 to vary the amount of air passing from branch supply line 94 to the line 106. As the loading air pressure in line 105 increases, the relay valve 85 permits a proportionately greater amount of air to pass into the line 106, and of course vice versa, a lesser amount of air as the loading air pressure in line 105 decreases.

The amount of air passing through line 106 and thence through branch line 107 controls the extent of the opening of diaphragm valve 62, thereby controlling the flow of steam through line 61 to the stoker engine 58 and consequently the speed of its operation and the amount of coal delivered to the firebox 14 by the stoker.

Air passing from the line 106 through the

branch line 103 effects a loading pressure on the relay valve 86, controlling passage of supply air from branch supply line 95 to the line 109 which in turn effects the operation of diaphragm valve 72 in the steam supply line 68 to the distributor jet manifold 69. The valve 72 is arranged to open fully at a low pressure, e. g. 7 lbs. per sq. in., and since an appreciable amount of time must elapse before a sufficient pressure is built up to operate the stoker engine 58, it is evident that the coal projecting steam blast from the distributor jet head 59 will come into operation before the stoker will operate.

Air from the 28 lb. per sq. in. branch supply line 99 enters the ratio controller 84 and leaves through the line 110 as a controlled loading air pressure for controlling the relay valve 87. The amount of air passing from the branch supply line 99 to the line 110 is controlled by a valve in the ratio controller, the setting of which is responsive to the controlled loading air pressure in the line 104. Thus the greater the loading air pressure in the line 104, in response to a greater demand for steam on the boiler, the more air will be admitted through the valve of the ratio controller 84 from the line 99 to the line 110.

The loading pressure of the air in the line 110 effects a loading pressure on the relay valve 87, controlling passage of supply air from branch supply line 96 to the line 111 which in turn effects the operation of the diaphragm valve 65 in the steam supply line 64 to the fan turbine 29. As the loading air pressure in line 110 increases, the relay valve 87 permits a proportionately greater amount of air to pass into the line 111, thereby opening the valve 65 a greater amount and admitting more steam to the fan turbine 29 to increase its speed. The speed of the turbine operated fan 31 is thus responsive to demand for steam on the locomotive boiler.

The diaphragm valve 65 is set to open at a lower pressure than the diaphragm valve 72, e. g., at 3 lbs. per sq. in., so that it is apparent that the fan turbine 29 will operate before steam is admitted to the distributor jet head 59, and before the stoker becomes operative.

At the same time that steam is admitted to the fan turbine 29 for operating the fan 31, steam is also admitted through branch line 67 to the damper cylinder 50 for opening the dampers 39 and 40. When the supply of steam to the fan turbine 29 is cut off, the supply to the damper cylinder 50 is also cut off, so that the dampers 39 and 40 close.

Preferably a governor 112 driven off the stoker engine 58 is employed for governing the speed of the stoker engine. An oil pressure is set up in the oil line 113 which opposes the pressure in the relay valve 85 of the loading pressure line 105. Thus if the stoker engine is operating at an excessive speed, the pressure in line 113 increases, and functions to restrict the amount of supply air passing through the relay valve 85, thereby partially closing the valve 62 and slowing up the speed of the stoker engine 58. It will be seen, therefore, that if a governor is employed, the amount of air which is allowed to pass through the relay valve 85 as an operating pressure on the diaphragm valve 62 is a function of the differential in pressure between the loading pressure line 105 and oil pressure line 113.

Means governing the speed of the fan turbine 29 is preferably also provided. This includes a pipe 114 leading from the combustion chamber of the firebox 14 to the ratio controller 84, 75 which is open when the draft fan starts to operate

and a pipe 115 leading from the smoke box 19 to the ratio controller 84. As the speed of the fan 31 increases a differential in pressure is set up between the combustion chamber and the smoke box which is communicated to the ratio controller 84 by means of the pipes 114 and 115, where this differential pressure is arranged to oppose the loading pressure from line 104, thereby limiting the amount of supply air passing from the branch supply line 99 to the line 110, which in turn functions to restrict the amount of supply air passing through the relay valve 87 thereby partially closing the diaphragm valve 65 and slowing up the speed of the fan turbine 29.

Preferably a lag device is interposed in the line 111 which leads to the diaphragm valve 65, to permit the fan 31 to operate for a short time after steam to the distributor jet head 59 has been cut off and the stoker engine has stopped. This includes a by-pass line 116 in the line 111, by-passing a check valve 117, with a needle valve 118 in the by-pass line 116. The check valve 117 permits air to pass to the diaphragm valve 65, but cuts off return of air, so that the air must pass through the needle valve 118 of the by-pass line 116. Thus while the valve 65 can open quickly, closing thereof is delayed.

From the above description it is apparent that the operation of the stoker, the distributor jets, 30 the draft fan, and the dampers is automatically controlled in accordance with demand for steam on the boiler.

Shifting from automatic control to manual control is accomplished through the selector valve 83, which can be manipulated to cut off the loading pressure from line 102 and can be manually operated to effect a desired loading pressure, thereby controlling the amount of air passing from the air supply branch line 98 through the 40 selector valve to the controlled loading pressure line 103. The rest of the control system will of course function as before.

The ratio controller 84 is provided with manually operated means whereby the ratio of air to coal may be changed. Optimum combustion conditions vary for different kinds of coal, some requiring more air than others, and by properly setting the ratio controller, the desired ratio of air to coal may be delivered.

50 The various instruments employed in the control system, the steam-pressure controller 82, selector valve 83, ratio controller 84 and relay valves 85, 86, 87, are well known in the art, and the details of construction are therefore not shown in the drawings or described.

From the description of the system, set forth in detail above, it is apparent that the amount of air induced by the fan as draft through the firebox and the amount of coal delivered by the 60 stoker are proportional to the demand being made upon the boiler for steam, the amount of coal and air in pre-selected ratio, being increased or decreased automatically as the demand on the boiler increases or decreases.

Other features include the automatic operation of the coal distributing jets when there is a sufficient demand for steam to cause functioning of the stoker engine and the draft fan and the 70 automatic cutting off of the coal distributing jets when the demand for steam is satisfied and operation of the stoker engine and draft fan ceases.

Ash pan dampers of the locomotive automatically open when the draft fan starts to operate

and automatically close when the draft fan stops.

Automatic sequential operation of the draft fan, the coal distributing jets and the stoker, in that order, is provided, whereby smoke is kept at a minimum.

While the invention has been described with reference to the specific embodiment disclosed and with reference to specific operating pressures, it will be obvious that changes may be made without departing from the spirit and scope of the invention.

I claim:

1. A combustion control system for use in a mechanically fired and drafted steam locomotive provided with a stoker fuel conveyor, a stoker fuel distributor and a draft producing blower, said system comprising air pressure loading means responsive to varying demands on the locomotive boiler for steam for effecting corresponding proportionate varying loading air pressures, supply lines for supplying operating pressure fluid to said conveyor, distributor and blower, and a pressure sensitive valve in each of said supply lines responsive to said varying loading air pressures for controlling operation of said conveyor, distributor and blower, said valves having different actuating sensitivity for sequential functioning of said blower, distributor and conveyor in that order.

2. A combustion control system for use in a mechanically fired and drafted steam locomotive provided with a stoker engine, a stoker distributor jet head and an induced draft fan turbine, said system comprising air pressure loading means responsive to varying demands on the locomotive boiler for steam for effecting corresponding proportionate varying loading air pressures, pressure sensitive valves in throttling relation to the steam supply of the stoker engine and fan turbine, said valves being responsive to said varying loading air pressures for correspondingly varying the speed of the stoker engine and fan turbine, and a pressure sensitive valve associated with the steam supply of the stoker distributor jet head, said last named valve being responsive to said varying loading air pressures for admitting steam to the stoker distributor jet head, said pressure sensitive valves having different actuating sensitivity for initial sequential functioning of the fan turbine, stoker distributor jet head and stoker engine, in that order.

3. A combustion control system for use in a mechanically fired and drafted steam locomotive provided with a stoker engine, a stoker distributor jet head, an induced draft fan turbine and an ash pan air damper operating motor cylinder, said system comprising air pressure loading means responsive to varying demands on the locomotive boiler for steam for effecting corresponding proportionate varying loading air pressures, supply lines for supplying steam to said stoker engine, distributor jet head, fan turbine and damper operating motor cylinder, pressure sensitive valves in throttling relation to the steam supply of the stoker engine and fan turbine, said valves being responsive to said varying loading air pressures for correspondingly varying the speed of the stoker engine and fan turbine, a connection from the steam supply of the turbine fan to the damper cylinder for controlling the position of the damper, and a pressure sensitive valve associated with the steam supply of the stoker distributor jet head, said last named valve being responsive to said varying loading air pressures

for admitting steam to the stoker distributor jet head.

4. A combustion control system for use in a steam locomotive provided with a pressure fluid operated stoker engine for driving the stoker coal conveying means, a pressure fluid blast emitting stoker distributor jet head for projecting the conveyed coal into the locomotive firebox, and a pressure fluid turbine driven fan for inducing draft through the firebox, said system comprising supply lines for delivering pressure fluid to the stoker engine, the stoker distributor jet head and the fan turbine, a pressure sensitive valve in each of said supply lines responsive to variations in pressure imposed thereon, an air pressure line communicating with each of said pressure sensitive valves, and air pressure loading devices associated with said air pressure lines responsive to variations in the boiler pressure of the locomotive for correspondingly varying the air pressure imposed on said pressure sensitive valves to control the passage of pressure fluid to said stoker engine, stoker distributor jet head and fan turbine, the pressure sensitive valve controlling functioning of the stoker distributor jet head being set to open fully at a pressure below the operating pressure of the stoker engine, and the pressure sensitive valve controlling functioning of the fan turbine being set to open at a pressure below the opening pressure of the pressure sensitive valve controlling functioning of the stoker distributor jet head, for sequential functioning of the fan turbine, stoker distributor jet head and stoker engine, in that order.

5. A combustion control system for use in a steam locomotive provided with a pressure fluid operated stoker engine for driving the stoker coal conveying means, a pressure fluid blast emitting stoker distributor jet head for projecting the conveyed coal into the locomotive firebox, and a pressure fluid turbine driven fan for inducing draft through the firebox, said system comprising supply lines for delivering pressure fluid to the stoker engine, the stoker distributor jet head and the fan turbine, a pressure sensitive valve in each of said supply lines responsive to variations in pressure imposed thereon for controlling passage of pressure fluid to said stoker engine, stoker distributor jet head and fan turbine, an air pressure supply line communicating with each of said pressure sensitive valves, air pressure loaded valves controlling the passage of air through said last named supply lines to said pressure sensitive valves, and means associated with an air pressure supply line responsive to variations in the demand on the locomotive boiler for steam, for proportionately controlling the loading air pressure on said air pressure loaded valves, and means responsive to the pressure differential between the smoke box and firebox of the locomotive for effecting a loading pressure opposing the loading pressure of the air pressure loaded valve associated with the fan turbine controlling pressure sensitive valve, whereby to impose a governing control on the speed of the fan turbine.

6. A combustion control system for use in a steam locomotive provided with a pressure fluid operated stoker engine for driving the stoker coal conveying means, a pressure fluid blast emitting stoker distributor jet head for projecting the conveyed coal into the locomotive firebox, and a pressure fluid turbine driven fan for inducing draft through the firebox, said system comprising supply lines for delivering pressure

fluid to the stoker engine, the stoker distributor jet head and the fan turbine, a pressure sensitive valve in each of said supply lines responsive to variations in pressure imposed thereon for controlling passage of pressure fluid to said stoker engine, stoker distributor jet head and fan turbine, an air pressure supply line communicating with each of said pressure sensitive valves, air pressure loaded valves controlling the passage of air through said last named supply lines to said pressure sensitive valves, and means associated with an air pressure supply line responsive to variations in the demand on the locomotive boiler for steam, for proportionately controlling the loading air pressure on said air pressure loaded valves; and means responsive to the speed of the stoker engine for effecting a loading pressure opposing the loading pressure of the air pressure loaded valve associated with the stoker engine controlling 15

governing control on the speed of the stoker engine.
